TAG FASTENER

Samuel Weiss, Brooklyn, N. Y.

Application December 28, 1935, Serial No. 56,460

5 Claims. (Cl. 40—25)

My invention relates to improvements in tag fasteners and it consists in the novel features which are hereinafter described.

One of the objects of my invention is to provide a fabric tag with a perfected means for fastening the same to a garment or a piece of linen in a way to prevent the disengagement of the garment from the fastener.

Another object of my invention is to prevent the disengagement of the tag from the fastener.

A further object is to prevent the laceration of garments and of the hands of operators by the protrusion of sharp points from the fastener.

A still other object of my invention is to have my improved tag fastener adapted to be made by mass production methods.

Another object is to reduce the thickness of the metal of which the fastener is made for a required degree of stiffness of the fastener, and, vice versa, to increase the stiffness of the fastener for a given thickness of the material of which the fastener is made.

A further object of my invention is to have said tag fastener simple, durable and inexpensive.

Other objects and advantages will hereinafter appear.

I attain these objects by the tag fastener, three forms of which are illustrated in the accompanying drawings, or by any mechanical equivalent or obvious modification of the same.

In the drawings Figs. 1, 2, 2a and 3 show one form of my tag fastener; Figs. 4, 4a, 5 and 6 show another form of my tag fastener, and Figs. 7 and 7a show a third form of my tag fastener.

Fig. 1 is a section on the line 1—1 of Fig. 3, looking in the direction of the arrows; Fig. 2 is a central vertical section of my improved tag fastener on the line 2—2 of Fig. 3, looking in the direction of the arrows, but showing the fastener partly closed and with a fragment of a fabric engaged thereby; and Fig. 2a is a view similar to Fig. 2, but showing the fastener closed.

Fig. 3 is a section essentially on the line 3—3 of Fig. 2, but showing the fastener in its original form with the two legs thereof substantially at right angles to each other.

Fig. 4 is a section on the line 4—4 of Fig. 6, looking in the direction of the arrows and Fig. 4a is a view similar to Fig. 4, but showing the fastener closed; Fig. 5 is a section on the broken line 5—5 of Fig. 4, looking in the direction of the arrows; and Fig. 6 is a section on the line 6—6 of either Fig. 4 or Fig. 5.

Fig. 7 is a central vertical section which is similar to Fig. 2 and Fig. 4 showing the fastener

partly open; and Fig. 7a is a view similar to Fig. 7, but showing the fastener closed.

Similar numerals refer to similar parts throughout the several views:

11 designates the tag in all the three modifications of my invention.

The tag 11 has therein an elongated opening 12 for passing therethrough one leg of the fastener, which is made of sheet metal and has the tag 11 secured to one leg thereof on the side of the latter 10 which faces the other leg by an eyelet rivet 13; and the latter also serves to receive therein a locking tongue 14, which is slotted from the other leg of the fastener, leaving therein an opening 16. The tongue 14 is passed through the opening 15 15 in the eyelet 13 when the fastener is secured to a garment, and the end of the tongue 14 is then bent over on to the outer surface of the first mentioned leg of the fastener.

The above described way of securing the tag 20 to the fastener is safer than the older way of securing the tag to the side of one leg of the fastener which is remote from the other leg. Each leg of the fastener has thereon a corrugated edge whereby fasteners made of light metal may 25 be made stiffer than they would be otherwise and thereby increasing the strength of the fastener; lighter metal may thereby be used, if desired, in the manufacture of my improved fastener.

The above described features are common to 30 all the three forms of my tag fastener which are hereinafter described.

In the form of my tag fastener, which is shown in Figs. 1, 2 and 3, 21 designates one leg of the fastener and 22 the other leg; the leg 21 has 35 slotted therefrom a combined piercing and locking tongue 23, leaving in said leg 21 a slot 24; the tongue 23 is located near the outer end of the leg 21 and is shown as disposed substantially at right angles to the surface of the leg 21 whereby 40 said tongue 23 may pierce a garment without being deflected thereby.

The leg 22 is shown as provided at the outer end thereof, and opposite to the said tongue 23, 45 with a curved shell-shaped shield 25 which is integral with said leg 22 and extends from the latter with the convex surface thereof towards the said leg 21 with the said tongue 23 thereon.

The shield 25 has therein an opening 26 to 50 fit said tongue 23, whereby a tight joint may be produced therebetween and encompassing the latter a depression 27, which serves to direct the end of said tongue 23 into the said opening 26 when said end happens to be brought into contact 55

with some point of the shield 25 outside of said opening 26.

A garment 30 is shown as engaged by said tongue 23, which is then made to pass through the said opening 26 when the two legs of the fastener are pressed towards each other, and the end of the tongue 23 is then bent into the housing or recess which is contained in the concave side of the shield 25, where it is hidden by the walls of the said shield 25 and kept out of reach of garments and the hands of operators, whereby the latter are protected from injury by said point.

The position of the shield 25 on the side of the leg 22 which is opposite the leg 21 shortens the part of the tongue 23 which is subject to bending strains when the fastener is closed, thereby increasing the resistance to separation of the garment 30 from the fastener and the opening of the legs 21 and 22 of the fastener.

20 In the modification of my tag fastener, which is shown in Figs. 4, 5 and 6, the combined piercing and locking tongue 33 is slotted from the leg 31, leaving therein a slot 34, and is disposed substantially at right angles to the leg 31 whereby 25 said tongue 33 may pierce a garment without being deflected thereby.

The leg 32 of the fastener has thereon a housing shield 35—36 and a deflector-shield 37—38, which is disposed with the shell 37 thereof extending outwardly or away from the leg 31 and with the passage 38 therein opening inwardly or towards the leg 31; the housing shield 35—36 has the shell 35 thereof extending inwardly or towards the leg 31, and the housing 36 opening 35 outwardly or away from the leg 31.

30 The housing shield 35—36 is positioned at the end of the leg 32 which is remote from its junction with the leg 31; and the deflector shield 37—38 is positioned at the end of the shield 35—36 which is nearer to the said junction of the legs 31 and 32.

When the fastener is closed, the end of the tongue 33 is deflected by the shield 37—38 into the plane of the leg 32 and in a direction away 45 from the said junction and is made to lodge in the housing 36 of the shield 35—36, which housing is also in the plane of the leg 32. Any pulling 50 stress or force exerted on the tongue 33 by a garment 30 will tend to tighten the tongue 33 in said shield 35—36 and will not loosen or detach it from the latter.

The part of the tongue 33 which engages a garment and is retained between the leg 31 and the leg 32 may be very short and therefore, strong 55 under bending strains.

The sides of the shield 35 serve to protect other garments and the hands of the operators from injury.

In the form of my tag fastener which is shown 60 in Fig. 7, the combined piercing and locking tongue 43 is slotted from the leg 41, leaving therein a slot 44, and is disposed substantially at right angles to the leg 41 whereby said tongue 43 may pierce a garment without being deflected 65 thereby.

The leg 42 has thereon a housing shield 45—46, a deflector shield 47—48 and a locking bar 49.

When the fastener is closed the end of the tongue 43 is first deflected by the concave side 70 47 of the shield 47—48, whereby it is bent or curled into a curved sickle-shaped bar, the end of which contacts with the side 46 of the shield 45—46 and is then still further deflected to the 75 side of the bar 49 which is opposite the leg 41,

whereby the tongue 43 is locked to the leg 42 of the fastener.

The locking action as above described may also be assisted by the hand of the operator.

In this last described modification the shield 5 45—46 also extends inwardly or towards the leg 41, whereby a very short part of the tongue 43 may be left between the leg 41 and the leg 42 when the fastener is closed or connected to a garment, thereby increasing the strength of the 10 connection thereof to a garment.

Variations are possible, and parts of my invention may be used without other parts.

I do not, therefore, restrict myself to the details as shown in the drawings. 15

I claim as my invention and desire to secure by Letters Patent:

1. A tag fastener made of sheet metal and having thereon a pair of legs and a tag attached to one of said legs on the side of the latter which is opposite the other leg, a means on said fastener for attaching a garment thereto, a locking tongue on one of said legs and an opening in the opposite leg for said tongue to pass therethrough and through said tag to secure said legs to each other with said tag held therebetween during the operation of attaching a garment to said fastener, thereby making said attachment more reliable and thereby holding said tag more securely in place on said fastener. 30

2. A tag fastener made of sheet metal and having thereon a pair of legs, a means on said fastener for attaching a garment thereto, an eyelet rivet and a tag secured thereby to one of said legs, a locking tongue on the other leg, 35 said eyelet rivet having therein an opening, for said locking tongue to pass therethrough and through said tag to secure said legs to each other during the operation of attaching a garment to said fastener, whereby said attachment is made 40 more reliable and thereby holding said tag more securely in place on said fastener.

3. A tag fastener made of sheet metal and having thereon a pair of legs, and a tag secured to one of said legs, a combined piercing and locking tongue, for engaging a garment thereby, slotted from the metal of one of said legs, and a curved shield on the other of said legs, said shield having the convex side thereof extending towards the first mentioned leg, said shield having 45 therein an opening to fit said tongue, for connecting the end of said tongue to said shield, thereby locking the said legs to each other and thereby housing the end of said tongue, to prevent injury thereby to goods or persons, and said 50 shield having therein a reentrant depression encompassing said opening, to guide the end of said tongue thereinto, the said position of the shield leaving a relatively short part of said tongue unhoused, thereby enhancing the strength 55 of the connection of said fastener to said garment.

4. A tag fastener made of sheet metal and having thereon a pair of legs joined to each other at one end thereof and a tag secured to one of said legs, a combined piercing and locking tongue for engaging a garment slotted from the metal of one of said legs, a housing shield and a deflector on the other of said legs, said housing shield being positioned at the end of said other leg which is remote from the junction of said legs and the deflector shield being positioned at the end of the housing shield which is nearer to the said junction and opposite the end of said tongue, whereby when the fastener is closed the 75

end of said tongue is to be deflected by the said deflector into the said housing shield and in the opposite direction from said junction, thereby increasing the resistance of said fastener to being forced open by a pull on said garment.

5. A tag fastener made of sheet metal and having thereon a pair of legs and a tag secured to one of said legs, a combined piercing and locking tongue for engaging a garment slitted from the 10 metal of one of said legs, an inwardly extending and outwardly concave shield on the other leg, a locking bar on said other leg in the plane thereof and an outwardly extending and inwardly

concave deflector on the said other leg, positioned opposite the end of said tongue, said deflector, said shield and said bar being so disposed with relation to each other, whereby when the fastener is closed said tongue is to be deflected and 5 the end thereof curved and inwardly deflected by said deflector and directed into contact with the concave side of said shield, to be further deflected by the latter and directed into a space there-between and said bar, thereby locking said tongue 10 to said other leg.

SAMUEL WEISS.
